UNITED STATES PATENT OFFICE.

ANDRÉ GUASCO AND ANGE CHUSIN, OF MARSEILLES, FRANCE.

FEED-INDICATOR FOR BOILERS.

SPECIFICATION forming part of Letters Patent No. 482,171, dated September 6, 1892.

Application filed October 8, 1891. Serial No. 408,113. (No model.) Patented in France July 7, 1890, No. 206,795; in Belgium August 17, 1891, No. 95,722; in England August 21, 1891, No. 14,128; in Germany September 29, 1891, No. 15,429; in Italy September 30, 1891, No. 30,427; in Spain November 7, 1891, No. 12,506, and in Austria-Hungary November 27, 1891, No. 39,823 and No. 68,465.

To all whom it may concern:

Be it known that we, ANDRÉ GUASCO and ANGE CHUSIN, citizens of the Republic of France, and residents of Marseilles, in said Republic, have invented certain new and useful 5 Improvements in Feed-Indicators, of which the following is a full, clear, and exact description.

This invention has been patented to us in 10 France July 7, 1890, No. 206,795; in Italy September 30, 1891, No. 30,427; in Spain November 7, 1891, No. 12,506; in Belgium August 17, 1891, No. 95,722; in Austria-Hungary November 27, 1891, No. 39,823 and No. 68,465; 15 in Great Britain August 21, 1891, No. 14,128, and in Germany September 29, 1891, No. 15,429.

The object of our invention is to provide 20 an indicator whereby the correct operation of the valve-check of pumps or boilers is assured.

In the accompanying drawings we have 25 shown in Figures 1 and 2 one type of feed-indicator with our improvements applied thereto. Referring to the drawings, our feed-indicator is composed of a hollow metallic tube T, in which is a movable rod a, bearing at its lower part a shoulder c, forming a valve and 30 surmounted by a movable index b. Above the index is a spring K, provided with two metallic round shields I I'. Two end pieces t t', fixed to an insulating-stopper M, bear the circuit-wires r r. A glass tube d, fixed by two tight mountings g g, permits of seeing 35 the movement of the index b. Every check-valve when working is moved on its seat with an alternate movement invisible and inaudible from the exterior. By means of the indicator this movement is made apparent by an 40 electric bell placed at a desired point, and which can be heard by everybody. The working of the bell is assured by the connection of the two end pieces t t', fixed on an insulating-stopper M, bearing the wires of the circuit 45 r r, by the metal shield I, attached to the spring K, which bears freely on the boss I' upon the index b of the movable rod a, which being also placed freely on the head of the valve e follows the movements of the latter. The distance 50 which separates the shield I from the end pieces

t t' being as small as desired, it follows that at the slightest movement of the valve the contact will take place and will last until the said valve shall again rest on its seat. The duration of the contact is assured by the spring K, 55 which permits of the rod moving freely. The movement of the valve is also made apparent by perforating the envelope of the indicator and by placing therein a glass tube d, fixed in two tight mountings g g. It is in this 60 glass tube that the index b moves, being visible through the glass. In both cases the lower part of the rod a bears a shoulder c, forming a valve to bear upon the seat 20, and destined to prevent the passage of the water 65 of the boiler into the upper casing in case of a breaking of the glass or of dismounting of the apparatus for any cause.

To put the apparatus in place, it suffices to 70 mount it in the axis of the valve-stem in the valve-box V, previously pierced for the reception of the movable rod.

In the course of working the body of the indicator forms an air-reservoir, so that the 75 movable parts are always visible in the tube-indicator, even though the feeding be done by a highly-colored liquid.

The form and the dimensions may be varied according to the use to which the device is put.

We claim as our invention—
1. In combination, the tubing T, screw-threaded at its lower end for attachment to its support, the insulating-cap M, closing the upper end of said tube, the terminals t t', carried by the said cap, the valve e and its casing, the movable stem a, operated thereby, the movable contact I, and the spring K, intermediate of the contact, and the movable stem a, substantially as described. 80

2. In combination, the tubing T, having 90 openings in its side, the valve e, with its casing, the movable stem a, carrying indicator b, the inner glass tube d, the terminals t t', the contact I, connected with the stem a, and the means for supporting the terminals closing the end of the tube and holding the parts in place, consisting of the insulated cap M, substantially as described. 95

3. In combination, the valve with its stem, the indicator b, the contact I, the interposed 100

spring between the contact and the indicator, and an electric circuit arranged to be opened and closed by the movable contact I, substantially as described.

5 4. In combination, the tubing T, the valve e, with its casing, the terminals t t', the insulating-cap M therefor, the contact I, the movable stem a, connected therewith to move the same to the terminals, and the valve c on the

lower end of the stem a, resting upon the stem 10 of the valve e, substantially as described.

In witness whereof we have hereunto set our hands in presence of two witnesses.

A. GUASCO.
A. CHUSIN.
